(57) **CLAIM**

The ornamental design for a vehicle pet barrier, as shown and described.

DESCRIPTION

FIG. 1 is a perspective view of the vehicle pet barrier;

FIG. 2 is front elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a rear elevational view thereof.

The broken lines shown in the drawings illustrate portions of the vehicle pet barrier that form no part of the claimed design.

1 Claim, 4 Drawing Sheets

FIG. 2

FIG. 7
